UNITED STATES PATENT OFFICE.

THOMAS TULLY, OF CLEVELAND, OHIO, ASSIGNOR, BY DIRECT AND MESNE ASSIGNMENTS, TO JOHN CROWELL, JR., AND G. WALTER SHUMWAY, BOTH OF GLENVILLE, OHIO.

SEWING-MACHINE.

SPECIFICATION forming part of Letters Patent No. 268,152, dated November 28, 1882.

Application filed August 10, 1882. (No model.)

To all whom it may concern:

Be it known that I, THOMAS TULLY, of Cleveland, in the county of Cuyahoga and State of Ohio, have invented certain new and useful

5 Improvements in Sewing-Machines; and I do hereby declare the following to be a full, clear, and exact description of the invention, such as will enable others skilled in the art to which it pertains to make and use the same.

10 My invention relates to sewing-machines; and it consists in the parts and combination of parts, as will be hereinafter fully set forth and claimed.

In the drawings, Figure 1 is an isometric view 15 of a sewing-machine embodying my invention. Figs. 2 and 3 are views in front elevation of my machine, showing the parts in different positions. Fig. 4 is a view in rear elevation of my machine, showing the manner of operating the reciprocating needle-arm. Fig. 5 is 20 a plan view, looking down upon the feed and looper of my machine. Fig. 6 is a detached view of a portion of my machine, showing more clearly the construction and operation of my 25 thread-guide. Fig. 7 is a plan view of the bottom of plate H, showing the spring thread-guide.

A is the bed of my machine.

B is the driving-shaft, which is journaled in 30 suitable bearings extending from the bed A. This shaft is provided at its rear end with an eccentric, C, and at its forward end with a crank-wheel, D.

E is the needle-arm of my machine, which is 35 pivoted at a to the upright E'. This arm E is operated by means of the eccentric C and yoke F, the arm b of which extends upward from said yoke F, being pivotally connected to the rear end of the arm E at b', (see Fig. 4,) and a 40 short arm, c, which extends downward from the yoke F, passing through a hole in the bed-plate A, as shown in Fig. 4. This construction prevents the yoke from slipping off of the eccentric and allows of a cheaply-constructed eccentric being used, obviating the use of flanges or guides thereon, which would otherwise be necessary, and thereby make it more costly.

G is the presser-foot arm, which is permanently secured to the bed A, extending upward

therefrom for a short distance, and then running parallel to it or horizontal, as shown in Fig. 1. The arm G acts to support the presser-foot G'.

H is a shelf or plate, which extends forward from the bed A and above the forward end of 55 the shaft B.

I is a bar, which is supported under the plate H in such a manner as to allow of its being reciprocated horizontally.

Secured to the bar I is a looper, J, which is so 60 located that as it is reciprocated it will pass in front of the needle and between it and the thread (this being done when the needle has passed downward to its lowest point) and retain the thread until the needle has again passed 65 upward. The bar I is driven or reciprocated by means of the crank-wheel D, it being connected thereto by the short pitman K.

Secured to the short pitman K are two upwardly-curved and sharp-pointed arms e f, 70 which act as a feed to move the goods along. These arms e f have the same movement as that end of the pitman K which is attached to the crank-wheel D. This movement is such as to raise the arms e f, and thus bring them 75 in contact with the goods, then move them to the left, (see Fig. 3,) and with them the goods. The arms e f are then lowered and moved to the right. This movement is gone through at each revolution of the crank-wheel D. 80

L is a thread-guide, (see Figs. 6 and 7,) which consists of a spring flattened at its point and inclined to an angle, so that as the needle passes through the plate H at the hole M it will strike this spring on its flattened surface, 85 presented as it is at an angle to the course of the needle. From this contact with the needle it is forced slightly to one side, and is held in that position by the needle during its downward stroke. Upon the upward stroke the 90 loop is retained by the looper J until the latter passes free from the loop. The spring L, being free, carries the loop to the opposite side by this return motion of the spring L, so that the loop is presented at an angle, so that at 95 the next downward stroke the needle passes through the loop, thus forming a chain-stitch.

M is a spool-tension, the construction of

which is old. It consists of two cones—one above and the other below the spool—and a binding-nut and spring, as shown. This acts to keep the thread at a proper tension, which may be either increased or diminished, as desired.

The operation of my machine is as follows: The goods to be sewed is placed beneath the presser-foot and the machine started. As the needle is driven downward the bar I and the looper J are moved to the left, as shown in Fig. 3. Now, when the needle has reached its lowest point and has started on its upward stroke the crank-wheel D acts, through the pitman K, to move the bar I and looper J to the right, (see Fig. 2,) thus causing the point of the looper J to pass between the thread and needle and retain the thread while the needle is passing upward. This acts to form a loop. When the needle has raised to a point above the goods the arms e,f of the feeder are in such a position as to come in contact with the under side of the goods, and, being operated by the crank-wheel D, as hereinbefore described, act to feed or move the goods to the left. As the feeder e,f is being moved to the left, so also is the looper J, which is attached to the bar I. This leaves the loop free to be drawn along by the cloth. Now, as the cloth is moved to the left and drawn with it (the loop) the direction of the said loop is changed to nearly a horizontal by the guide L, (see Fig. 6,) thus leaving the loop in position to allow of the needle on its downward stroke to pass through and form the chain-stitch.

What I claim is—

1. In a sewing-machine, the combination, with a crank-wheel, of a pitman connected thereto, said pitman being provided with de-

vices for engaging and feeding the goods to be sewed, substantially as set forth.

2. In a sewing-machine, the combination, with a looper and crank-wheel and pitman for operating the looper, of a thread-guide adapted to be actuated by the needle and allow the latter to pass through the loop on its down-stroke, substantially as set forth.

3. In a sewing-machine, a driving-shaft provided on one end with means for operating a vibrating arm and at its other end with means for operating a pitman, said pitman in turn operating both the feed and looper, substantially as set forth.

4. In a sewing-machine, the combination, with a driving-shaft provided with a crank, a sliding bar, and a pitman, of curved arms rigidly secured to the pitman and adapted to engage and feed the cloth, substantially as set forth.

5. In a sewing-machine, the combination, with the needle, of a thread-guide consisting of a spring secured at one end, and constructed with an inclined free end arranged and adapted to be moved by the engagement of the needle therewith, substantially as set forth.

6. In a sewing-machine, the combination, with a crank-wheel, of a feeder and looper, both being operated by one and the same pitman, substantially as and for the purpose shown and described.

In testimony whereof I have signed my name to this specification in the presence of two subscribing witnesses.

THOMAS TULLY.
